(57) **CLAIM**

The ornamental design for a lash tester wand, substantially as shown and described.

DESCRIPTION

FIG. 1 is a top, front and side perspective view of our new design for a lash tester wand;

FIG. 2 is a front elevational view of the lash tester wand shown in FIG. 1;

FIG. 3 is a rear elevational view of the lash tester wand shown in FIG. 1;

FIG. 4 is a side elevational view of the lash tester wand shown in FIG. 1;

FIG. 5 is the opposite side elevational view of the lash tester wand shown in FIG. 1;

FIG. 6 is a top end view of the lash tester wand shown in FIG. 1;

FIG. 7 is a bottom end view of the lash tester wand shown in FIG. 1; and,

FIG. 8 is a schematic illustration of the lash tester wand, shown in FIG. 1 in use, wherein the broken lines shown in the figure are provided for illustrative purposes only and form no part of the claimed design.
